ASH REMOVING OUTLET AND DOOR FOR
HEATERSElliott S. Waddell, Columbus, Ga., assignor to
Columbus Iron Works Co., Columbus, Ga., a
corporation of Georgia

Application June 26, 1940, Serial No. 342,552

6 Claims. (Cl. 126—242)

The present invention relates to ash removing outlets and doors for heaters, and more particularly for use in wood burning heaters.

As heretofore practiced in wood burning heaters, the removal of ashes has been effected through the top of the heater which is inconvenient, laborious and inefficient.

An important object of the invention is to provide an ash removal outlet and door which is not subject to the disadvantages above mentioned.

Another object of the invention is to provide an ash outlet and door which in closed position will be air tight.

A further object of the invention is to provide an ash outlet and door which is simple and inexpensive and which is easily installed.

A still further object of the invention is to provide an ash outlet and door which may be applied to existing heaters.

Other objects and advantages will be apparent during the course of the description that follows.

In the drawings, like parts are denoted by similar reference characters throughout the several views.

Figure 1 is a side elevational view of the invention applied to a wood burning stove.

Figure 2 is a front elevational view of Figure 1.

Figure 3 is a top plan view of the outlet and door therefor.

Figure 4 is a front elevational view with the ash door in closed position.

Figure 5 is a front elevational view with the ash door in open position.

Figure 6 is a side elevational view of the parts shown in Figure 4.

Figure 7 is a rear elevational view of the parts shown in Figure 4, and

Figure 8 is a vertical sectional view taken on the line 8—8 of Figure 4.

Referring more particularly to the drawings, the numeral 10 designates a wood burning heater provided at the top with an opening having a cover 11 for the insertion of fuel and with an opening 12 in the top for the attachment of a stove pipe 13.

The heater is designed to contain a bed of sand or ashes on which the fire is built and on which it burns, and preferably in a plane with or slightly above the surface of the bed of sand or ashes is the bottom of the draft opening. Secured to the heater within or around the draft opening is the draft elbow 14. This elbow is rigidly secured to the stove by screws or rivets and is provided on its upper face with an opening 15 surrounded by a collar or flange 16 removably secured to the

elbow 14 by fastenings 17. A draft flue or pipe 18 is mounted on the collar 16 and may be secured thereto by rivets or the like if desired.

The draft flue 18 may be of any desired shape and extends approximately from the plane of the top of the stove to the top of elbow 14. Conventional air inlets 19 and control means 20 therefore are provided at the top of the draft tube 18 while a damper having control means 21 is provided within the draft tube.

As shown in detail by Figures 3 to 8, the elbow 14 of draft tube 18 is utilized to provide the removal outlet by providing on its outer inclined face an opening 22. This opening 22 is in substantial alinement with the draft opening of the heater which in turn is in a plane with the fuel consumed in heater 10.

The opening 22 also forms the frame for a door 23 which has its inner portion recessed to accommodate a plate 24 provided with a continuous flange 25. This flange is snugly received within the opening 22 to provide an air-tight closure for same. In order that the plate 24 may be readily replaced it is removably attached to the door by bolts 26 and nuts 27.

On its outer face the door 23 is provided with an integral central radial rib 28 having a cam face 29. The lower end of the rib 28 projects beyond the door to form an arm 30 which is received between spaced ears 31 of a bracket 32. Suitable openings are provided in arm 30 and ears 31 to enable a pin 33 to be received therein to form a hinged or swinging connection for the door.

The bracket 32 is detachably secured to the lower portion of the elbow 14 by a bolt 34 and nut 35 whereby it may be readily attached or detached therefrom if desired. The distance between ears 31 is greater than the width of arm 30 thus giving the door a lateral play to aid its alinement with the opening 22 when assuming a closed position.

To retain the door in closed position and to further insure an air-tight closure for opening 22 a yoke 36 is pivotally connected to elbow 14 by a rod 37. The yoke straddles the elbow with its closed end 38 having a limited swinging movement over the outer face of the elbow 14 and door 23.

The uppermost central portion of the elbow 14 is also provided with an integral radial rib 39 having a cam face 40 in alinement with the radial rib 28 and cam face 29 on the door 23. The rib 39 is within the swinging range of the

yoke 36 and closed end 38 thereof for a purpose now described.

As particularly shown in Figure 5, when access is desired to the interior of the heater 10 for the purpose of removing ashes or starting a fire, the yoke 36 is swung upwardly beyond the confines of the door 23. In this position the door gravitates downwardly to expose the opening 22 for the purpose stated. In order to retain the yoke in its up or inoperative position, the inner face of its closed end 38 is brought into engagement with the cam face 40 of rib 39. Any further upward movement of the yoke is resisted by the cam face with the result that the yoke will be frictionally held in binding engagement with the cam face of rib 39.

When it is desired to close the opening 22, the door is alined with the opening and the yoke given a slight tap to release it from engagement with cam face 40. The yoke swings downwardly until it engages the rib 28 of door 23. Downward movement of the yoke is resisted by the cam face 29 so that a slight downward pressure of the yoke will force and retain the door into intimate engagement with its frame to provide an air-tight closure for the outlet 22. This is very important in that when the door is closed the outlet must be air-tight so as to continue to force air into the heater through the draft tube 18 and elbow 14.

The present outlet and door being part of the elbow 14 may be applied to existing heaters without any modification of the heater as is obvious.

All of the parts making up the elbow outlet and closure are made of suitable heat resisting material in any suitable manner such as casting. Preferably, the door 23, rib 28 and arm 30 are cast integrally to eliminate expense and provide a strong construction. In the same manner elbow 14 and rib 39 are similarly formed.

It is obvious that various changes and modifications may be made in the details of construction and design of the above specifically described embodiment of this invention without departing from the spirit thereof, such changes and modifications being restricted only by the scope of the following claims.

What is claimed is:

1. An elbow for the draft opening of a heater, said elbow being provided with an outlet opening in alinement with said draft opening, a hinged door on said elbow for closing said outlet opening, cam members on the outer face of said door, second cam members on the upper outer face of said elbow, and a yoke capable of up and down movement carried by said elbow, said yoke in its down position engaging said first mentioned cam members to frictionally retain said door closed over said outlet opening, said second mentioned cam means frictionally retaining said yoke in its up position when said door is open.

2. In a heater having a draft opening, an air directing member over said opening and secured to the heater, said member being provided with

an outlet opening in alinement with said draft opening, a hinged door for said outlet opening normally biased to open position, a yoke secured to said member for swinging movement over said door when in closed position, means on the door engaged by said yoke to frictionally retain said door over said outlet opening, and means on said member for frictionally retaining said yoke out of engagement with said first mentioned means.

3. In a heater having a draft opening, an elbow secured over said opening, a draft tube mounted on the elbow and communicating with the interior of the heater through the draft opening, said elbow having an outlet opening in alinement with the draft opening, a hinged door normally biased to open position for closing said outlet opening, cam means on said door, cam means on said elbow, and a member mounted for swinging movement on said member and adapted to selectively engage the first mentioned cam means when the door is in closed position for frictionally retaining the door in closed position, and the second mentioned cam means when the door is in the normally biased open position.

4. An elbow for the draft opening of a heater, said elbow being provided with an outlet opening in alinement with said draft opening, a hinged door on said elbow for closing said outlet opening, means extending from the outer face of said door, means extending from the upper outer face of said elbow, and a member mounted for movement over said means, said member in one position engaging said first mentioned means for retaining said door closed over said outlet opening and in another position engaging the second mentioned means to be retained out of the path of said door.

5. An elbow for the draft opening of a heater, said elbow having an outlet opening in its outer face and in alinement with the draft opening, a door carried by said elbow and adapted to cover and uncover said outlet opening, a cam member on the outer face of said door, a second cam member carried by said elbow and in substantial alinement with said first mentioned cam member, and a swinging member frictionally engageable with the first mentioned cam member when the door covers said outlet opening to retain same closed air-tight, said member frictionally engaging said second cam means when the door is opened.

6. An elbow for the draft opening of a heater, said elbow having an outlet opening in alinement with the draft opening, a door carried by said elbow and adapted to cover and uncover said outlet opening, cam means on said door, cam means on said elbow, and a member secured to said elbow for up and down movement over said door and elbow, said member in its down position adapted to engage the first mentioned cam means to retain the door closed over said outlet opening and engaging the second mentioned cam means in its up position to be retained thereby when the door is opened.
